(Model.)

H. W. HUKE & F. P. WESTON.
KNITTING MACHINE NEEDLE.

No. 600,692.

Patented Mar. 15, 1898.

UNITED STATES PATENT OFFICE.

HERMAN W. HUKE AND FREDERICK P. WESTON, OF TORRINGTON, CONNECTICUT, ASSIGNEES TO THE EXCELSIOR NEEDLE COMPANY, OF SAME PLACE.

KNITTING-MACHINE NEEDLE.

SPECIFICATION forming part of Letters Patent No. 600,692, dated March 15, 1898.

Application filed June 7, 1897. Serial No. 639,644. (Model.)

To all whom it may concern:

Be it known that we, HERMAN W. HUKE and FREDERICK P. WESTON, citizens of the United States, residing at Torrington, in the county of Litchfield and State of Connecticut, have 5 invented an Improvement in Knitting-Machine Needles, of which the following is a specification.

Needles for knitting-machines have been 10 made with a slot or mortise receiving a latch having an eye at one end, and a pivot-pin is passed through the eye. The latch must swing with freedom upon the pivot-pin; but in practice the pivot-pin is liable to become 15 loose and project, and if there is any projection or bur at either end of the pivot-pin it is liable to injure the fibers of the yarn.

Various efforts have heretofore been made 20 to secure the pivot-pin into the needle in such a manner that the same is not liable to become loose, and with this object in view the pivot-pin has been sufficiently short for the metal of the needle to be closed inwardly 25 against the ends of such pin. The pin has been riveted up with the spread ends in conical countersinks and the central part of the pivot enlarged by the end pressure, and in some instances the metal of the needle has 30 been counterbored at the ends of the pivot-hole, so that the heads of the rivet have been spread into the counterbores, with the surfaces of the heads below the surrounding surfaces of the needle, and the central portion of the pivot enlarged, and in other instances 35 the ends of the pivot have been spread or headed up by concave dies in order that the edges of the riveted-up heads might be below the surrounding surfaces of the needle. The pivot-pin has also been screw-threaded 40 within the tapped or screw-threaded holes in the body of the needle. In all these different forms in which the pivot-pins have been secured we have found difficulties to exist either in the manufacture of the needles or 45 from the pivots becoming worn or loose and projecting so that the fibers of the yarn are injured by the ends of the pivot-pins.

By the present invention we are enabled to 50 secure the pivot-pins in the needles in the most permanent and reliable manner and at

the same time to protect the ends of the pivot-pins from contact with the fibers of the yarn by dressing off or removing the ends of such pivot-pins, so that they are below the surrounding surfaces of the needle.

55

In carrying out the present improvements the needle is made in the usual manner, with a mortise or slot receiving the eye of the latch, and the pivot-pin is passed through the holes in the needle and through the eye of the latch, and such pivot-pin is rigidly secured in position either by riveting up the ends of such pivot-pin or by screwing the same into the tapped holes of the needle, and the ends of such pivot-pin are dressed off, so that they 60 are below the surrounding surfaces of the needle. Thereby the edges of the pivot-pin at the ends are sufficiently below the normal surfaces of the needle to remain out of contact with the fibers of the yarn, and such yarn 65 is protected from any projections or roughness that may arise from the pivot-pin becoming loose or in consequence of the needle being bent or straightened and thereby tending to form burs or roughness of any character 70 at the ends of the pivot-pin.

We prefer to dress off or finish the ends of the pivot-pin by revolving tools or cutters and simultaneously to remove sufficient of the metal immediately adjacent to the ends 75 of the pivot-pin for leaving the surface of such needle above and closely adjacent to the edges of the ends of the pivot-pin, so that should there be or arise any roughness of such ends it will be sufficiently below the normal surfaces of the needle to be out of contact with the fibers of the yarn, thus protecting such fibers of the yarn from injury, and by these improvements the damage from the pivot-pin becoming loose is reduced to a minimum. 80

In the drawings, Figure 1 illustrates a knitting-needle with the present improvement. Fig. 2 is a section, and Fig. 3 a side elevation, representing in magnified size the pivot 85 of the latch after the same has been riveted up in one of the well-known forms. Fig. 4 is a section, and Fig. 5 an elevation in a similar magnified size, of a pivot-pin after the ends of the pivot and the surrounding metal have 90 95 100

been dressed off or otherwise formed substantially flat and below the surrounding surfaces of the needle. Fig. 6 is a section, and Fig. 7 an elevation, illustrating the present improvement when the ends of the pivot are dressed off or removed by circular cutters, grinders, or mills revolving on axes perpendicular to the axes of the pivot-pin; and Fig. 8 is a section, and Fig. 9 an elevation, of a screw-threaded pivot-pin with the ends similarly removed or ground off.

In some instances the countersinks in the needle at the ends of the pivot-holes are longest in the direction of the length of the needle, as illustrated in Fig. 3, in order that the pivot may not be liable to turn after the ends have been spread or riveted up in any desired manner, and in some cases the middle portion of the rivet will be spread or enlarged in consequence of the upsetting of the pivot-wire by the end pressure in riveting up the head, and in other instances the wire will not be enlarged in the middle in the act of riveting up the ends of such pivot-wire, but will remain substantially uniform in diameter, as illustrated in Fig. 4, and where the pivot-wire is screwed into the tapped or screw-threaded holes in the needle, as illustrated in Fig. 8, it is advantageous to apply a pressure at the ends of the pivot-wire, so as to slightly enlarge the screw-threaded pivot-wire and cause it to bind firmly into the holes in the needle. The central part of the pivot-wire may also be enlarged by the end pressure. In all instances the ends of the pivot-wire are finished off by suitable tools and with a revolving motion, so as to leave the ends of the pivot-wire below the surrounding surfaces of the needle.

In Figs. 4 and 5 the ends of the pivot-wire are represented as substantially flat and at the bottom of circular recesses, rotary tools being provided which revolve substantially in line with the axis of the pivot-wire, so as

to dress off or finish the surface of the metal 45 at the ends of the pivot-wire and leave the same at a sufficient distance below the surrounding surface of the needle to effectually prevent injury to the fibers of the yarn should there ever arise or be left a roughness at the 50 edges of the spread heads or ends of the pivot.

In Figs. 6, 7, 8, and 9 the ends of the pivot-wire are represented as dressed off by rotary cutters, grinders, or tools, the axes of which are perpendicular to the axis of the pivot-wire, such tools being sufficiently wide to dress off or remove the ends of the pivot-wire to a sufficient distance below the surrounding surfaces of the needle to effectually prevent injury to the yarn from the edges at the ends 60 of the pivot-wire, such recesses being substantially segments of cylinders.

By the present improvements the knitting-needles are rendered much more reliable and durable and the risk of injury to the fibers of 65 the yarn is reduced to a minimum.

We claim as our invention—

1. A knitting-machine needle recessed at the ends of the latch-pivot, and the ends of the pivot-wire dressed off to coincide with the 70 surfaces of the needle at the bottoms of the recesses, substantially as set forth.

2. A knitting-machine needle having a circular recess at each end of the latch-pivot and the end of the pivot-wire coinciding with the 75 bottom surfaces of the recesses, substantially as specified.

3. A knitting-machine needle recessed in its sides and at the ends of the latch-pivot, and the ends of the pivot-wire spread and coinciding with the bottom surfaces of the recesses, substantially as specified.

Signed by us this 2d day of June, 1897.

HERMAN W. HUKE.

FREDERICK P. WESTON.
